UNITED STATES PATENT OFFICE.

ALEXANDER B. MOHLER, OF MEXICO, MEXICO.

ENGINE-VALVE.

1,088,609.

Specification of Letters Patent. Patented Feb. 24, 1914.

Application filed January 20, 1912. Serial No. 672,424.

To all whom it may concern:

Be it known that I, ALEXANDER B. MOHLER, a citizen of the United States, residing at Mexico, Federal District, Republic of Mexico, have invented a new and useful Engine-Valve, of which the following is a specification.

This invention has reference to improvements in explosion engines, and its object is to provide a valve structure wherein the valve ports are relatively large and wherein power losses due to valve construction are in a large measure eliminated.

In accordance with the present invention the inlet and exhaust ports of the engine, which is of the four cycle type, are controlled by slide valves separately but relatively actuated. These valves are provided with large passages through them which when brought into coincidence with each other and with the ports they control provide ample space for the charge and for the escape of the gases of combustion. These valves are so arranged as to slide easily with relation one to the other and to a housing for the valves, while provision is made for the ready removal of the valves for inspection or repairs, which latter may be made at a minimum cost, and in a minimum of time, while the general appearance of the motor is improved, and, moreover, the construction is such that the valves may be thoroughly water jacketed, thus keeping them comparatively cool and free from the troubles resulting from excessive expansion of the metal under the action of heat.

The invention will be best understood from a consideration of the following detailed description, taken in connection with the accompanying drawings forming a part of this specification, with the understanding, however, that while the drawings show two practical embodiments of the invention, the latter is by no means limited to any exact conformity with the showing of the drawings, but may be embodied in other forms so long as there is no marked departure from the scope of the invention.

In the drawings: Figure 1 is an elevation of an engine with the improved valve structure applied, some parts being omitted for clearness of illustration. Fig. 2 is a vertical section through the upper end of an engine cylinder and valve structure applied thereto. Fig. 3 is a plan view of one end of a multi-cylinder engine with the cylinder

head removed and a portion of the valve crank case also removed, the holding bolts and other parts being shown in section. Fig. 4 is a longitudinal section of a portion of a multi-cylinder engine on the line 4-4 of Fig. 1, but drawn to a larger scale. Fig. 5 is a perspective view of one of the valves controlling the inlet and exhaust ports. Fig. 6 is an elevation partially in section of a modified form of engine construction so far as the valve mechanism is concerned. Figs. 7, 8, 9 and 10 are views partly in section and partly in diagram of the valves and valve actuating mechanism to illustrate the different phases of the valve movements.

Referring to the drawings there is shown an engine provided with a cylinder or cylinders 1 in accordance with whether the engine is of the single or multi-cylinder type, and in the particular form of engine shown it is provided with a crank case 2, crank shaft 3, fly wheel 4, supporting webs 5, magneto 6, pump 7 for the cooling water, and suitable driving mechanism for the valve structure, which in the showing of Fig. 1 is hidden because inclosed in casing members 8, 9, 10 and 11, the valve driving mechanism also serving as a means for driving a shaft 12, which at one end carries the rotor of the pump 7 and at the other the armature of the magneto 6. The structures so far described may be taken as typical of any suitable form of explosion engine of the four cycle type.

The cylinder portion of the engine is provided with a water jacket 13, which in the main may follow the usual practice, and each cylinder has lodged therein a piston 14 which may correspond to pistons as usually employed in explosion engines. One side of the explosion end of each cylinder is entered by a passage 15 for a spark plug indicated at 16 in Fig. 1.

The invention being applicable to either a single cylinder or a multi-cylinder engine, the description of the invention will in the main be confined to a single cylinder, since the description of one cylinder will apply to all of the cylinders. The explosion chamber end of the cylinder is provided with an inlet port 17 and an exhaust port 18, the two ports being separated by a hollow web 19 having a passage 20 through it communicating with the interior of the water jacket 13 surrounding the cylinder, so that each port

is water jacketed, while the web 19 performs an additional function to be referred to hereinafter. The ports are elongated in parallel relation and are located on opposite sides of a diameter of the cylinder, the latter being circular, as is customary, and in this manner the area of each port may be materially greater than the area of a circular port, such as is commonly employed where puppet valves are used. At opposite ends of the ports and extending perpendicular to the length of these ports the cylinder structure is provided with ribs 21 forming between them a channel 22 open at both ends, and of a depth equal to the height of the ribs. Applied to the ribs 21 is a cylinder head 23 which for a multi-cylinder engine may be long enough to cover all the cylinders. This head is supported by the ribs 21 and may be secured to the ported end of the cylinder by bolts 24. It is desirable that the depth of the channel 22 be variable at will within suitable limits, wherefore there are introduced between the supporting surfaces of the ribs 21 and the cylinder head a suitable number of very thin liners or shims 25, and by adding to the number of these liners or removing one or more of them, the depth of the channel 22 is very readily varied. The head 23 has extending therethrough conduits 26, 27, provided with passages or ports 28, 29, respectively, matching the respective ports 17 and 18, but spaced from the latter by a distance equal to the depth or thickness of the channel 22. The conduit 26 is designed to convey fuel to the cylinder through the matching ports 28 and 17 and the conduit 27 constitutes the exhaust conduit communicating with the interior of the cylinder through the passages 29 and 18. It will be understood, of course, that the fuel conduit 26 is in communication with a suitable source of fuel and that the exhaust conduit 27 may be connected to an exhaust pipe for the proper disposition of the products of combustion by way of a muffler, if desired, when the engine is used upon an automobile. The interior of the head 23 is provided with a water chamber 30 which may receive or discharge water through a pipe 31, while the water jacket 13 is connected to the pump 7 by a pipe 32. While the cooling chambers have been referred to as water jackets, it will be understood that this term is employed largely in a typical sense, since other cooling mediums besides water may be utilized. The channel 22 is, so far as the engine cylinder and head 23 are concerned open at both ends, and one end is closed by a cap plate 33 of sufficient extent to project for a distance on to the water jacket of the engine cylinder and on to the head 23, and this cap plate is provided with a channel 34 having its ends opening through passages 35, 36, respectively, into the interior of the water

jacket 13 and the chamber 30 in the head 23, whereby there may be established a circulation of water or other cooling medium from the jacket 13 to the chamber 30 or in the contrary direction, as may be desirable. 70 Access to the channel 22 is readily obtainable by the removal of the plate 33. While not shown, it will be understood, of course, that suitable packing is provided between the plate 33 and the parts with which it engages, and at all other parts of the engine where packing is advisable, and since this is the common practice in explosion engines, no further mention thereof is deemed necessary. 75 80

Lodged within the channel 22 are two plates 37, 38; the plate 37 being provided with two ports 39 and 40, respectively, while the plate 38 is provided with two ports 41, 42, respectively, the ports 39 and 40 being closer together than the ports 41 and 42 and all the ports being of the same dimensions both with respect to each other and with respect to the ports 17 and 19 in so far as the showing of the drawing is concerned, but it will be understood that while the ports 17, 28, 39 and 41 should be all of the same, or approximately the same size, and the ports 18, 29, 40 and 42 should likewise be of the same or approximately the same size, it is not mandatory that the two sets of ports should be of the same size, or even approximately the same size. The two plates 37 and 38 constitute slide valves and are together of a thickness to snugly yet freely fit within the channel 22 with respect to the depth of such channel and of a width to snugly, yet freely, fit within the channel with respect to its width. 90 95 100

Mounted at one side of the channel 22 is a crank shaft 43 having bearings 44, preferably anti-friction bearings, at each end in supporting members 45. The shaft 43 is provided with two crank portions 46, 47, respectively, carrying pitmen 48 connected to respective extensions 49 of the two slide valves 37 and 38, these extensions being on respectively opposite sides of the center line of the valves, so that they may pass each other, thus permitting the compacting of the valve structure. The crank shaft 45 is housed in a casing 50 having a cover 51 which may be made readily removable, and this casing is so shaped as to provide a pocket 52 for lubricant, so that the crank shaft with the parts carried thereby, and the valves 37 and 38, may be lubricated by the splash system, this forming a convenient means of lubrication. It will be understood, of course, that any other convenient system of lubrication for the valves 37 and 38 may be adopted. 110 115 120 125

One end of the crank shaft 43 carries a worm gear wheel 53 meshing with a worm 54 on a shaft 55 receiving motion from the 130

crank shaft 3 through the transmission gearing before referred to, but which is not shown in detail, the arrangement being such, as is customary, that the valves shall be 5 operated in proper relation to the crank shaft 3 in accordance with the usual timing in four cycle engines, except that with the valve structure of the present invention the relative opening and closing of the valves 10 may have a slightly different relation than in the case of puppet valves. The crank shaft 43 in its rotation causes a reciprocatory movement of the two slide valve plates 37 and 38, and the relation of movement of these two plates will be best understood from a consideration of Figs. 7 to 10. The angular displacement of the cranks 46 and 47 is about seventy-one degrees, although this particular displacement need 20 not be mandatory, but has been found to impart to the slide valves the desired relative movements. In each of Figs. 7 to 10 the cranks 46 and 47 are considered as rotating clockwise, wherefore the valves 37 25 and 38 will be reciprocated to the right and left as viewed in these figures. As shown in Fig. 7 the valve 38 which is connected to the crank 47 is moving to the right at its greatest speed, while the valve 37 which is connected to the crank 46 is also moving to the right, but at a slow speed due to the relation of the two cranks to the dead center. From 30 this point on until the crank 47 reaches the dead center line, the valve 37 is accelerating in speed and the valve 38 is slowing up and when the crank 47 passes the dead center line, which in the position shown in Fig. 8 is the three o'clock position, the valve 38 begins its movement toward the left, while the 35 valve 37 continues its movements toward the right. This condition of affairs continues with an acceleration of the movement of the valve 38 and the slowing up of the valve 37 until the crank 46 reaches the three 40 o'clock position, and then both valves move toward the left until the crank 47 reaches the six o'clock position, when the valve 38 will begin to slow up, while the valve 37 accelerates, the valve 37 attaining its highest 45 speed when the crank 46 reaches the six o'clock position, and when crank 47 reaches the nine o'clock or dead center position the valve 38 begins its movement toward the right and continues with increasing speed, 50 while the valve 37 continues its movement toward the left with decreasing speed, until finally the crank 46 reaches the nine o'clock position, beyond which point the valve 37 moves toward the right with accelerating speed, 55 while the valve 38 is moving toward the right with accelerating speed until the crank 47 reaches the twelve o'clock position as considered with relation to Fig. 7.

The valves 37 and 38 in Fig. 7 have their 60 ports 39 and 41 approaching the closed po-

sition while the port 42 of the valve 38 is blanked by the plain portion of the valve 37 then interposed between the ports 42 and 29. Both the inlet and exhaust passages for the cylinder are thereby closed and remain closed during the power stroke of the piston of the cylinder which is assumed to be then taking place, the parts being then approximately in the position shown in Fig. 8. During the return or scavenging stroke 70 of the piston the valves move to the position shown in Fig. 9 where the ports 40 and 42 are approximately in a line one with the other and with the ports 18 and 29, thus permitting a free escape of the products of combustion. The arrangement is such that the exhaust ports close after the crank shaft has passed the top center by ten degrees, while the inlet ports open on the exact up center of the crank shaft, wherefore there is an overlap of the inlet and exhaust ports during this ten degrees of movement and the inflowing fuel would have a tendency to fly directly across to the exhaust port, while the same is exhausting, which tendency, however, is prevented by the web 19. 75 In the position of the parts shown in Fig. 7, the exhaust port is closed and the inlet port is about to close. In Fig. 8 there is shown the position of the parts during the firing period of stroke. In Fig. 9 the valves are shown with the exhaust port open, and this is during the scavenging stroke, while in Fig. 10 the inlet port is about to open with the exhaust port closed. 80 85 90 In Fig. 6 the valves 37 and 38 are upright and move parallel with the longitudinal axis of the cylinder instead of perpendicular thereto, as in the structure shown in the other figures. In this construction the 95 cap portion of the cylinder is not necessarily a separate member, but may be cast in one piece with the cylinder, as indicated at 56, while the ports 17 and 18 at the end of the cylinder of Fig. 2 are replaced by 100 ports 17^a and 18^a at one side of the cylinder which is provided with a laterally expanded portion 57 for the accommodation of these ports, and to this laterally expanded portion 57 there is applied a member 23^a 105 which may be in substantially all respects similar to the cylinder head 23 of the other figures, and in so far as the parts correspond, they are indicated in Fig. 6 by the same reference numerals. At an appropriate point the engine of Fig. 6 carries a crank shaft 43^a which may be similar to the crank shaft 43, and this shaft is connected by pitmen 48^a with the slide valves. Instead of transmitting power from the main 110 crank shaft 3 of the engine to the crank shaft 43^a by worm gear, a silent chain drive 58 may connect the crank shaft 3 with the crank shaft 43^a, while the pitmen 48^a and portions 49^a of the slide valves extending 115 120 125 130

beyond the cap 23^a are inclosed by a suitable removable casing 59, whereby access to the valve crank shaft and the valves may be had at any time by the removal of the casing 59.

The valves 37 and 38 are, where liable to the action of the heat generated by the explosions, surrounded by water, so that the expansion and contraction will be almost equal to that of the surrounding metal. The two plates constituting the valves may be quite thin, so that the expansion in the direction of the depth of the valve channel is small. The expansion in the direction of the width of the valves is negligible, since the two plates may have plenty of clearance in the valve channel, so that binding will never occur.

The drawings show the valve 37 with ports 39 and 40 closer together than the ports 41 and 42 of the valve 38, the latter-named valve being the one adjacent the explosion chamber of the engine. This is the arrangement which is employed when the crank shaft driving the valves rotates in a certain direction. Should the crank shaft driving the valves rotate in the opposite direction with the main crank shaft of the engine rotating in the same direction as before, then the valves 37 and 38 are reversed in position, that is, the valve 37 is close to the explosion chamber of the engine instead of the valve 38 in order that the movements of the valves may occur in proper timed relation to the reciprocation of the engine piston.

With the present invention the engine follows the lines of the ordinary explosion engine to the explosion chamber ends of the cylinders and the valves have the same general relation to the cylinder or cylinders as is found in the great majority of explosion engines. Should there occur a heavy demand upon the engine, as when used upon a racing automobile or for hill climbing contests, or under some similar conditions, the slide valves may be afforded a little more clearance by loosening up the bolts holding the cylinder head in position, so that even though there should be a greater expansion than usual, due to the heating up of the engine because of the heavy load put thereon, the valves will still run as freely as before, since the clearance is always ample, or may be made so without reducing the efficiency of the engine where there is a liability of a prolonged heavy demand upon the engine.

What is claimed is:—

60 1. An explosion engine of the four cycle type provided with adjacent inlet and exhaust ports having flat associated slide valves movable one on the other and in traversing relation to the said ports and each provided with a pair of adjacent ports,

and means for actuating the valves in timed relation through the cycles of operation of the engine.

2. A four cycle explosion engine provided with adjacent inlet and exhaust ports and continuations thereof matching said ports with a valve chamber between said ports and their continuations, associated slide valves lodged in the valve chamber and each provided with a pair of adjacent ports, and means for actuating the valves to bring the ports into and out of matching relation one with another and with respective engine ports in timed relation relative to the cycles of operation of the engine. 70 75

3. An explosion engine provided with a cylinder having adjacent inlet and exhaust ports at one end, a head provided with inlet and exhaust ports matching those of the cylinder and said cylinder and head defining a valve chamber, ported substantially flat plates adapted to the valve chamber when in face engagement one with the other, and means for moving the plates in the valve chamber in traversing relation to the matching ports of the cylinder and head to bring the ports in the plates into and out of matching relation one to the other and with the cylinder and head ports in timed relation to the movements of the engine. 80 85 90

4. An explosion engine provided with inlet and exhaust ports and two valves in the form of flat plates slidable one on the other in traversing relation to the inlet and exhaust ports, each valve being provided with two ports movable into and out of matching relation with ports of the other valve and with the inlet and exhaust ports of the engine, the ports of one plate being spaced differently from those of the other. 95 100

5. An explosion engine provided with adjacent inlet and exhaust ports, two valves each in the form of a plate and movable one on the other in traversing relation to the engine ports, each plate being provided with two adjacent spaced ports movable into and out of matching relation with the ports of the other valve and with the said inlet and exhaust ports, and means for imparting variable speed reciprocatory movements to the valves. 105 110 115

6. An explosion engine provided with inlet and exhaust ports, two valves each in the form of a plate and movable one on the other in traversing relation to the engine ports, each plate being provided with two spaced ports movable into and out of matching relation with the ports of the other valve and with the engine ports, and means for imparting variable speed reciprocatory movements to the valves, the ports in one valve being in closer relation than those of the other valve. 120 125

7. An explosion engine having a cylinder provided with adjacent inlet and exhaust 130

- ports, a cap member for the ported portion of the cylinder also provided with adjacent ports matching those of the cylinder and with passages for fuel and products of combustion, the cylinder and cap member being provided with internal chambers for a cooling medium and the cylinder being provided with a channel for a cooling medium between the adjacent ports, substantially flat slide valves in traversing relation to the ported portion of the cylinder and the cap member therefor, said slide valves having ports, and means for moving the slide valves in timed relation to bring the ports of the valves into and out of matching relation to the inlet and exhaust ports of the cylinder.
8. An explosion engine provided with a cylinder having adjacent inlet and exhaust ports at the explosion chamber end, a cap member for the ported portion of the cylinder, said cap member having adjacent ports matching those of the cylinder and with the cylinder defining a valve chamber, the cylinder and cap member having chambers therein for the circulation of a cooling medium, and the cylinder having a channel for a cooling medium intermediate of the adjacent ports, substantially flat slide valves adapted to the chamber between the cap member and ported end of the cylinder with the valves in face contact and each provided with adjacent ports, and means for reciprocating the valves to bring their ports into matching relation one to the other and with the respective cylinder ports in timed relation to the movements of the engine piston.
9. An explosion engine provided with a cylinder having adjacent inlet and exhaust ports at the explosion chamber end, a cap member for the ported portion of the cylinder, said cap member having adjacent ports matching those of the cylinder and with the cylinder defining a valve chamber, the cylinder and cap member having chambers therein for the circulation of a cooling medium, and the cylinder having a channel for a cooling medium intermediate of the adjacent ports, substantially flat slide valves adapted to the chamber between the cap member and ported end of the cylinder with the valves in face contact and each provided with adjacent ports, and means for reciprocating the valves to bring their ports into matching relation one with the other and with the respective cylinder ports in timed relation to the movements of the engine piston, the cylinder, cap and valve ports being elongated in one direction and the valves being movable in a direction transverse to the elongation of the ports.
10. An explosion engine having a cylinder with adjacent inlet and exhaust ports and a channel into which the ports open, a cap member for the ported portion of the cylinder constituting a cover member for the
- channel and provided with adjacent ports matching those of the cylinder, and reciprocatory slide valves each having adjacent ports spaced differently from those of the other and both provided with driving connections to movable parts of the engine and adapted to the channel between the cylinder and cap member.
11. An explosion engine having a cylinder with adjacent inlet and exhaust ports and a channel into which the ports open, a cap member for the ported portion of the cylinder constituting a cover member for the channel and provided with adjacent ports matching those of the cylinder, and reciprocatory slide valves each having adjacent ports spaced differently from those of the other and both provided with driving connections to movable parts of the engine and adapted to the channel between the cylinder and cap member, said slide valves being each in the form of a flat plate.
12. A four cycle explosion engine having adjacent inlet and exhaust ports elongated transversely to the direction of flow of material therethrough, and a pair of reciprocable associated slide valves each in the form of a flat plate with a plurality of adjacent elongated ports therein adapted to match the ports of the cylinder, the direction of reciprocation of the valves being perpendicular to the elongation of the ports.
13. A four cycle engine having adjacent inlet and exhaust ports elongated transversely to the direction of flow of material therethrough, and a pair of reciprocable associated slide valves each in the form of a flat plate with a pair of adjacent elongated ports therein adapted to match the ports of the cylinder, the direction of reciprocation of the valves being perpendicular to the elongation of the ports, the engine on the explosion chamber side of the valves being provided with passages for the flow of a cooling medium in surrounding relation to the ports.
14. An explosion engine provided with a cylinder having adjacent inlet and exhaust ports, a detachable cap member for the ported portion of the cylinder and also provided with adjacent intake and exhaust passages matching the intake and exhaust ports of the cylinder, the cylinder and cap member defining an open ended channel between them, a cover member for one end of the channel and connected to the cylinder and the cap member, respectively, substantially flat slide valves adapted to the channel and comprising plates movable one on the other with each provided with a pair of ports corresponding to the ports of the cylinder and the matching passages of the cap, the ports of one slide valve being differently spaced from those of the other and means for reciprocating the plates one on the other within

the channel to open and close the inlet and exhaust ports in proper timed relation.

15. An explosion engine provided with a cylinder having adjacent inlet and exhaust ports, a detachable cap member for the ported portion of the cylinder and also provided with adjacent intake and exhaust passages matching the intake and exhaust ports of the cylinder, the cylinder and cap member defining an open ended channel between them, a cover member for one end of the channel and connected to the cylinder and the cap member, respectively, slide valves adapted to the channel and comprising substantially flat plates movable one on the other with ports corresponding to the ports of the cylinder and the matching passages of the cap, and means for reciprocating the plates one on the other within the channel to open and close the inlet and exhaust ports in proper timed relation, the cylinder being provided with a water jacket having a water channel between the ports, the cap member being provided with a water chamber surrounding the passages therethrough and the cover plate being provided with a water passage therethrough connecting the water jacket of the cylinder with the water chamber of the cap member.

30 16. An explosion engine having the end wall of the explosion chamber provided with adjacent ports, a cap member for the ported end of the cylinder also provided with matching ports and defining a channel between the cap member and the ported end of the cylinder, said channel being open at both ends and both the cap member and cylinder being provided with water jackets, a closure for one end of the channel provided with a passage constituting a means of communication between the water jackets of the cylinder and the cap member, a casing forming a closure for the other end of the channel, substantially flat slide valves lodged in the channel and each provided with adjacent ports movable into matching relation with the ports of the other and with the ports of the cylinder and cap member, respectively, and actuating mechanism for the slide valves housed in the casing.

17. An explosion engine having adjacent ports in the end wall of the explosion chamber, a cap member provided with ports matching those of the cylinder and with intake and exhaust channels communicating with said ports, the ported end of the cylinder and the ported portion of the cap member defining an open ended channel and both the cylinder and cap member being provided with water spaces, a closure for one end of the channel having a passage therethrough constituting a means of communication between the water spaces of the jacket and cap member, a casing covering the other end of the channel, two flat slide

valves movable one on the other and housed in the channel and each provided with ports movable into matching relation to the ports of the cylinder and cap member, respectively, the ports of one slide valve being differently spaced from those of the other, and actuating mechanism for the slide valves housed in the casing.

18. An explosion engine having adjacent ports in the end wall of the explosion chamber, a cap member provided with ports matching those of the cylinder and with intake and exhaust channels communicating with said ports, the ported end of the cylinder and the ported portion of the cap member defining an open ended channel and both the cylinder and cap member being provided with water spaces, a closure for one end of the channel having a passage therethrough constituting a means of communication between the water spaces of the jacket and cap member, a casing covering the other end of the channel, two flat slide valves movable one on the other and housed in the channel and each provided with ports movable into matching relation to the ports of the cylinder and cap member, respectively, the ports of one slide valve being differently spaced from those of the other, and actuating mechanism for the slide valves housed in the casing, the ports in the cylinder, cap and slide valves being elongated in a direction transverse to the direction of reciprocation of the slide valves and the actuating means being constructed to cause the reciprocation of the valves one on the other to open and close the inlet and exhaust ports in proper timed relation.

19. An explosion engine of the four cycle type provided with associated flat slide valves having substantially plane faces in contact and each traversed by a pair of adjacent ports, the engine being also provided with adjacent inlet and exhaust ports both on one side of the associated slide valves and having matching continuations of said ports on the other side of the associated slide valves, and means for reciprocating said slide valves in timed relation with respect to the cycles of operation of the engine.

20. In an internal combustion engine, the combination of a cylinder, a valve seat in the head of said cylinder, intake and exhaust ports in said head of said cylinder, a lower sliding valve plate adapted to be moved across said valve seat, ports in said valve plate adapted to be brought into operative relation with said intake and exhaust ports, a second sliding valve plate superimposed upon said lower valve plate, ports in said second sliding valve plate adapted to be brought into operative relation with said ports in said lower sliding valve plate, and with said intake and exhaust ports, and means whereby said sliding valve plates may be

actuated in a manner whereby their movements are so timed that said intake and exhaust ports are made alternately operative.

21. In an internal combustion engine, a cylinder, ports in said cylinder, a valve seat on the top of said cylinder, a sliding valve plate adapted to be moved thereon, a casting superimposed about said valve plate, a means for actuating said sliding valve plate 10 and a removable member opposite the free end of said valve plate, upon the removal of which member a deposit of carbon may be withdrawn.

22. In an internal combustion engine the

combination of a cylinder, a sliding valve 15 means mounted on the top of said cylinder, means for actuating said sliding valve means and an oil container adapted to provide a constant oil bath at the end of said valve plates.

In testimony, that I claim the foregoing as my own, I have hereto affixed my signature in the presence of two witnesses.

ALEXANDER B. MOHLER.
